Filed July 29, 1966, Ser. No. 3,266

Term of patent 14 years

(Cl. D81—10)

FIG. 1

FIG. 3

FIG. 1 is a perspective view, as seen from the front and top, of a heater for warming comestibles such as pretzels or the like embodying my new design.

FIG. 2 is a perspective view thereof, as seen from the right, front corner, and looking down at the top thereof, and

FIG. 3 is a similar view thereof, as seen from the left, front corner, and also looking down at the top thereof.

The rear walls of both the upper and the lower sections of the heater are plain.

I claim:

The ornamental design for a heater for warming comestibles such as pretzels or the like, as shown and described.
